CLOCK

Rudolph M. Babel, Pawtucket, R. I., assignor to
General Electric Company, a corporation of
New York

Application May 14, 1953, Serial No. 25,006

Term of patent 14 years

(Cl. D42—7)

To all whom it may concern:

Be it known that I, Rudolph M. Babel, have invented a new, original, and ornamental Design for a Clock, of which the following is a specification, reference being had to the accompanying drawing, forming a part hereof.

In the drawing the single figure is a front perspective view of a clock embodying my new design. The opposite side of the clock is the same in appearance as the side shown and the back thereof is substantially plain having extending therefrom suitable adjusting knobs.

I claim:

The ornamental design for a clock, as shown and described.
